Primary Examiner — Lauren R Calve(74) *Attorney, Agent, or Firm* — CANTOR COLBURN LLP(57) **CLAIM**

The ornamental design for a clothes hanger, as shown and described.

DESCRIPTION

FIG. 1 is a front perspective view of a clothes hanger, showing our new design;
 FIG. 2 is a front view thereof;
 FIG. 3 is a rear view thereof;
 FIG. 4 is a left-side view thereof;
 FIG. 5 is a right-side view thereof;
 FIG. 6 is a top view thereof;
 FIG. 7 is a bottom view thereof;
 FIG. 8 is a bottom perspective view thereof;
 FIG. 9 is an enlarged view of the portion 9 in FIG. 1;
 FIG. 10 is an enlarged view of the portion 10 in FIG. 1;
 FIG. 11 is an enlarged view of the portion 11 in FIG. 2;
 FIG. 12 is an enlarged view of the portion 12 in FIG. 2;
 FIG. 13 is an enlarged view of the portion 13 in FIG. 4;
 FIG. 14 is an enlarged view of the portion 14 in FIG. 4;
 FIG. 15 is an enlarged view of the portion 15 in FIG. 6;
 FIG. 16 is an enlarged view of the portion 16 in FIG. 7;
 FIG. 17 is an enlarged view of the portion 17 in FIG. 8; and,
 FIG. 18 is an enlarged view of the portion 18 in FIG. 8.
 The even-dash broken lines illustrating portions of a clothes hanger form no part of the claimed design. The dot-dash broken lines encircling enlargement portions of the claimed design form no part of the claimed design.

1 Claim, 18 Drawing Sheets(56)
